UNITED STATES PATENT OFFICE.

JOHN H. KARSTETTER, OF ALTOONA, PENNSYLVANIA.

PNEUMATIC MUSIC-SHEET CONTROL FOR PLAYER PIANOS.

Application filed January 5, 1923. Serial No. 610,834.

To all whom it may concern:

Be it known that JOHN H. KARSTETTER, a citizen of the United States, residing at Altoona, in the county of Blair and State of Pennsylvania, has invented certain new and useful Improvements in Pneumatic Music-Sheet Controls for Player Pianos, of which the following is a specification.

This invention relates to automatic controllers for the music sheets of player pianos.

The invention has as its general object to provide a pneumatic device which will operate to automatically maintain the music sheet of a player piano properly coordinated with the tracker bar during the playing of a selection and thereby obviate the discords which are produced when the sheet travels unevenly or shifts across the tracker bar in its travel.

One of the primary object of the invention is to provide means which will operate automatically to coordinate the traveling sheet with the tracker bar and to maintain the same so coordinated during the entire time of the travel of the sheet over the tracker bar, the means being so constructed and operating in such a manner as to obviate shifting of the sheet across the bar an undue distance.

Another object of the invention is to provide in apparatus of this class a novel pneumatic control which will operate with precision and in a most efficient manner.

In the accompanying drawings:

Figure 1 is a view in elevation of the apparatus embodying the invention installed, so much of the mechanism of the instrument being shown as is necessary to illustrate the application of the invention;

Figure 2 is a perspective view illustrating the pneumatic control and the prime mover associated therewith, the parts being relatively separated;

Figure 3 is a bottom plan view of the upper section of the chest of the pneumatic control;

Figure 4 is a top plan view of the lower section of said chest;

Figure 5 is a vertical longitudinal sectional view through the chest of the pneumatic control and the prime mover associated therewith;

Figure 6 is a vertical transverse sectional view taken substantially on the line 6—6 of

Figure 5 looking in the direction indicated by the arrows;

Figure 7 is a plan view of the cap of the inlet head for the chest;

Figure 8 is a plan view of the said head with the cap removed;

Figure 9 is a transverse sectional view taken substantially on the line 9—9 of Figure 8.

In the drawings, the numeral 1 indicates the tracker box of any ordinary player piano and in which box is mounted the usual tracker bar 2 and the music sheet rolls 3 and 4 which are respectively the storage roll and the take-up roll. The storage roll 3 for the music sheet, which sheet is indicated by the numeral 5, is supported in any of the conventional ways so that it may have limited shifting movement longitudinally, it being yieldably urged in one direction by a spring 6 located at one end of the spool and being adapted to be shifted in the opposite direction, against the tension of said spring, by means which will presently be described. The tracker bar 2 is provided with the usual perforations 7 and in addition, at each end of the series of perforations 7, with two perforations, one indicated by the numeral 8 and one by the numeral 9. Preferably these perforations are of triangular form and are arranged each with one side presented toward the adjacent end of the tracker bar, and the perforation 9 is laterally displaced inwardly with relation to the companion perforation 8. The openings 8 are so spaced that they will both be completely covered by the marginal portions of a music sheet of standard width so long as the sheet is traveling over the edge of the tracker bar in a uniform manner. In controlling apparatus of this class, means is employed to act automatically upon the storage roll 3 to longitudinally adjust the same and maintain the music sheet properly coordinated with the tracker bar during the travel of the sheet past the bar, the means being operable to shift the said roll and the sheet upon uncovering of the openings corresponding to the openings 8 in the present invention, and the invention contemplates the employment of a novel pneumatic chest and arrangement of valves therein for effecting this result, as will now be explained.

In the drawings, the pneumatic chest is indicated in general by the numeral 10 and the same is provided with a distributing head indicated in general by the numeral 11. This head comprises a body 12 and a

cap plate 13 which is removably secured upon the upper side thereof, an air-tight fit being obtained by the employment of a gasket or packing 14. Tubes 15, 16, 17 and 18 are fitted at one end into openings in the cap plate 13, and by reference to Figure 1 of the drawings it will be observed that the tube 15 leads from the opening 8 at one end of the tracker bar, the tube 16 from the corresponding opening at the other end of the tracker bar, the tube 17 from the opening 9 at the first-mentioned end of the bar, and the tube 18 from the opening 9 at the second-mentioned end of the bar. The body 12 of the distributing head 11 is shown clearly in plan in Figure 8 of the drawings and by reference to this figure and to Figure 9 it will be observed that the said body is formed at intervals in its length with vertically extending air passages 19. Ducts 20, 21, 22 and 23 are formed vertically in the body and communicate by lateral passages 24 with the lower ends of respective ones of the passages 19, and when the head 13 is assembled with the body 12, the ends of the tubes 15, 16, 17 and 18 will be placed in communication with the upper ends of the ducts 20, 21, 22 and 23, respectively. A straining medium, such, for example, as a disc of wire gauze 25, is arranged within the upper portion of each air passage 19 and above the plane of this disc these air passages are placed, by way of lateral passages 26, in communication with the upper ends of ducts 27, 28, 29 and 30, these ducts being located diagonally opposite the respective ducts 20, 21, 22 and 23, as shown in the said Figures 8 and 9. The distributing head 11 is secured upon the upper side of the pneumatic chest 10, and the lower ends of the ducts 27, 28, 29 and 30 are in this manner placed in communication respectively with ducts 31, 32, 33 and 34 which are formed in a series in the upper section 35 of the pneumatic chest 10, it being observed, by reference to the drawings, that this chest comprises in addition to the upper section 35 a lower section indicated by the numeral 36 and that these sections are disposed in assembled relation and secured together face to face in any suitable manner, gaskets 37 being interposed between their meeting faces to provide an air-tight fit.

55 The upper face of the lower section 36 of the pneumatic chest is formed with spaced chambers 38 and 39, and positioned within these chambers are diaphragms 40 and 41, respectively, which are of thin leather or some other flexible material. A duct 42 is formed in the said section 36 and communicates at one end with the lower end of the duct 31 in the upper section 35 and at its other end with the chamber 38 beneath the diaphragm 40. A bleed duct 43 communi-

cates at one end with the chamber 38 above the diaphragm 40 and at its other end with the duct 31, and is of considerably less dimensions than the said duct 31. A duct 44 is also formed in the lower section 36 of the pneumatic chest and communicates at one end with the duct 32 and at its other end with the chamber 39 beneath the diaphragm 41. Openings 45 and 46 are formed in the upper section 35 of the pneumatic chest and communicate at their lower ends, respectively with the chambers 38 and 39 above the diaphragms 40 and 41 in these chambers, and these openings 45 and 46 respectively accommodate the stems 47 of valves which are indicated respectively in general by the numerals 48 and 49. The valve 48 comprises, in addition to the stem 47, heads 50 and 51 fixed respectively at the lower and upper ends of its stem 47 and provided with facings 52 and 53 of any suitable packing material. The valve 49 comprises heads 54 and 55 fixed respectively at the lower and upper ends of its stem 47 and provided with packing facings 56 and 57. In their normal positions, the valves 48 and 49 seat with their heads 50 and 54 respectively resting upon the diaphragms 40 and 41, the packing facings 53 and 57 of the heads 51 and 55 of said valves resting upon the upper surface of the section 35 and closing the upper ends of the openings 45 and 46, respectively. As there is a reduced pressure in the chambers 38 and 39, under normal conditions, the diaphragms 40 and 41 will normally assume the sagged position shown in Figure 6, thus permitting the valves 48 and 49 to assume the positions stated, the valves being maintained in this position not only by gravity but also by reason of the atmospheric pressure on their heads 51 and 55. Normally, therefore, the chest is closed to the atmosphere. A bleed duct 58 is provided in the top section 35 of the pneumatic chest and communicates at one end with the chamber 39 above the diaphragm 41 and at its other end with the duct 32 and is of dimensions considerably less than those of the said duct 32, the bleed ducts 43 and 58 serving to normally equalize the pressure on the opposite surfaces of the diaphragms 40 and 41.

The upper face of the lower section 36 of the pneumatic chest is formed with two sets of chambers 59 and 60, the chambers of each set being placed in communication with each other by a passageway 61 formed in said section 36. Ducts 62 and 63 are formed in the upper section 35 of the pneumatic chest, and ducts 64 and 65 are formed in the lower section 36 of said chest. One end of the duct 62 communicates with the opening 45 and the other end of the duct 62 communicates with one end of the duct 64, the other end of said duct 64 communicat-

ing with one of said chambers 59. The duct 63 communicates at one end with the opening 46 and at its other end with the duct 65, and the other end of said duct 65 communicates with the other one of the chambers 59. Flexible diaphragms 66 are arranged over the chambers 59, and upon the under side of each diaphragm is a packing facing 67 which, when the diaphragm is collapsed or sagged, as shown in Figure 5, seats over and closes the end of the duct 64 or 65 as the case may be. The numeral 69 indicates a head which is fixed upon the upper side of each diaphragm 66, and, in connection with the facing 67, forms a valve. Chambers 70 and 71 are formed in the under side of the upper section 35 of the pneumatic chest and are closed on their under sides by diaphragms 72 and 73, respectively. The said upper section 35 is formed with a duct 74 which constitutes an extension from the duct 34 and communicates with the chamber 70 above the diaphragm 72. This section is also formed with a duct 75 which constitutes a continuation or extension of the duct 33 and communicates with the chamber 71 above the diaphragm 73. A bleed duct 76 leads from the chamber 70 and opens at the under side of the section 35, and a bleed duct 77 leads in like manner from the duct 75 and opens through the under side of the said section 35, all the bleed ducts opening into the reduced pressure chamber formed between the opposed faces of the sections 35, 36. By reference to Figs. 3, 4 and 5 of the drawings it will be observed that the diaphragms 72 and 73 and the chambers 70 and 71 with which they are associated are of greater diameter than the respective chambers 59 and the active areas of their respective diaphragms 66, the chamber 59 being directly below the chambers 70 and 71. Small bleed vents 78 are provided in the lower section 36 of the pneumatic chest and establish communication between the ducts 61 and the space above the diaphragms 66. Diaphragms 79 are arranged above the chambers 60 and normally assume the sagged position shown in Figure 5 of the drawings. Above each of the chambers 60 and diaphragms 79, the upper section 35 of the pneumatic chest is formed with an opening 80 through which loosely extends the stem 81 of a valve indicated in general by the numeral 82. Heads 83 and 84 are fixed to the stem 81 of each of said valves at the lower and upper ends thereof, respectively, and are provided with packing facings 85 and 86, respectively, it being observed by reference to the said Figure 5 that normally the packing facing 86 of each valve will rest upon the upper surface of the section 35 of the pneumatic chest and close the upper end of the respective opening 80. A duct 87 leads laterally from each

opening 80 and is placed in communication with a respective duct 88 formed in the upright head 89 of a prime mover which is indicated in general by the numeral 90, a nipple or sleeve 87 being provided to couple the ducts 87 and 88.

The prime mover referred to above, is preferably in the form of a double bellows comprising, in addition to the head 89, an intermediate partition wall 91 and side walls 92, the space between the said walls 91 and 92 being bridged by the webs 93 of the bellows and thus closed to the atmosphere. The intermediate or partition wall 91 of the bellows is rigidly mounted and secured by means of screws or other suitable fastening devices 94, upon the head 89 of the prime mover, whereas the side walls 92 are suitably hingedly mounted upon said head so that they may have movement relative to the said intermediate or partition wall. The pneumatic chest is secured to the head 89 by screws inserted through the lower corners of the head into screw holes provided in the corresponding corners of the chest. The ducts 88 are so arranged, as will be evident by reference to Figure 5 of the drawings, that each will communicate with a respective one of the two pockets of the bellows. The numeral 95 indicates a pipe which is led through the lower portion of the head 89 of the prime mover and through the end of the lower section 36 of the pneumatic chest and communicates with the space within the chest above the diaphragms 79 and 66. The pipe 95 leads to the exhaust wind chest of the instrument.

The numeral 96 indicates a bridge member, which is secured upon the upper sides of the walls 92 of the bellows, constituting the prime mover, and this bridge piece is preferably formed with an opening 97 in which loosely fits the lower end of an arm 98 which depends from one end of a rod or shaft 99 supported for rocking movement within the tracker box above the roll 3. The other end of the shaft 99 is provided likewise with a depending arm 100 which has a laterally inwardly turned lower end 101 engaging in an opening in an arm 102 mounted at its lower end, as at 103, for swinging movement. The upper end of the arm 102 is located opposite the adjacent end of the spindle for the spool 3 and the said arm is provided at its said end with a head 104 which constitutes in effect a cam for coaction with the said end of the spool spindle in the rocking movement of the arm 102, it being understood that when the arm is swung in one direction, the cam head 104 will be so moved as to permit of lateral displacement of the spool 3 under the influence of the spring 6 and that when the arm is swung in the opposite direction, the cam head will ride

against the end of the spindle for the said spool and will shift or displace the spool longitudinally in the opposite direction and against the tension of the said spring.

5 By reference to Figure 1 of the drawings it will be observed that when a music sheet of standard width is employed and the sheet is free from marginal defects and is properly coordinated with the tracker bar, all of the 10 openings 8 and 9 will be closed by the marginal portions of the sheet. However, should the sheet become displaced with relation to the tracker bar, during its travel thereover, from any cause whatsoever, one 15 or more of said openings will be uncovered with the result that the pneumatic control will operate automatically to restore the sheet to its coordinated position. Under 20 normal conditions all of the openings 8 and 9 will be closed, as stated, and inasmuch as both ducts 88 which are in communication with the air pockets of the bellows comprising the prime mover, are likewise in communication, by way of the openings 80, 25 with the space above the diaphragms 66 and 79, and the exhaust tube 95 is also in communication with this space, there is reduced pressure to like degree in both sides of the bellows and therefore the side walls 92 30 thereof will be maintained in position equidistantly spaced from the intermediate or partition wall 91. Likewise, under these conditions, the arm 102 will maintain an intermediate position in which the end of 35 the spindle for the spool 3 will engage against the mid-portion of the cam head 104, and so long as these conditions prevail, the parts will remain at rest. However, if, in the travel of the music sheet 40 over the tracker bar, the sheet becomes displaced or laterally shifted, or there is any tendency toward such shifting, and if for example, under these conditions, the opening 8 at the right hand end of the tracker bar in Figure 1 is uncovered, air under atmospheric pressure will enter through the said opening 8 and will pass through the tube 15 to the duct 20 from which it will 45 pass, by way of the passage 24, into the passage 19. Passing upwardly through the screen or straining medium 25, which removes all particles of dust, the air will pass by way of the passage 26 into the duct 27 and from this duct through the duct 31 50 and duct 42 into the chamber 38 at which time it will act upon the diaphragm 40 to lift the same and with it the valve 48. When this valve is lifted the lower end of 55 the opening 45 will be closed and the upper end of said opening will be uncovered to the atmosphere so that air under atmospheric pressure may enter through the opening and pass through the ducts 62 and 64 and 60 into the adjacent chamber 59 where, acting against the diaphragm 66, it will lift the

same, together with the head 69 thereon. At this time the diaphragm 79 will be lifted and with it the valve 82 thus closing the lower end of the opening 80 and exposing the upper end of the opening to the atmosphere. As there is reduced pressure in the pockets of the bellows, air under atmospheric pressure will enter through the opening 80 and ducts 87 and 88 and into that one of the pockets with which the said valve 82 is associated to expand said pocket. This will influence movement in unison of the two side walls 92 of the bellows through the connecting bridge and, as the bellows walls move in the manner stated, slight 80 rocking motion will be imparted to the shaft or rod 99 and will be communicated finally to the arm 102, in the rocking movement of which the cam head 104 will be moved with relation to the end of the 85 spindle for the upper spool 3 and in a manner to permit the spring 6 to act to laterally shift the said spool 3 to the right in the said Figure 1.

Practically immediately upon shifting of 90 the sheet in the manner stated and to such an extent as to partly uncover the opening 8 at the other end of the tracker bar, air will be momentarily admitted through the pipe 16 into the pneumatic chest and the 95 associated valve parts will be operated to establish equilibrium in pressure within the two sides of the bellows so that the music sheet will be thus coordinated with the tracker bar and maintained in such relation.

Under other conditions the music sheet might be so narrow that in traveling evenly over the tracker bar both of the openings 105 8 would be exposed or uncovered. It will be evident from the foregoing that with both openings uncovered air under atmospheric pressure would fill both pockets of the bellows and the sheet shifting means would therefore be in equilibrium. Should the sheet move laterally, as for example toward the left, its right hand margin, in Figure 1, would uncover the corresponding opening 9. Upon uncovering of this opening, air under 110 atmospheric pressure will enter through the tube 17 and pass through the ducts 22, 24, 115 19, 26, 29 and 33 to the duct 75 and thence into the chamber 71 above the diaphragm 73, bulging the diaphragm downwardly and causing it to exert pressure in a downward 120 direction against the respective head 69 causing the valve disc 67 to close the discharge end of the duct 65 thus shutting off the supply of air to the associated chamber 60, the air which has been trapped in said chamber 60 being bled through the respective bleed orifice 78 thus permitting the diaphragm 79 to collapse and allowing the valve 82 to seat in the position shown in 125 Figure 5 of the drawings. This movement 130

of the valve serves to cut off the supply of air under atmospheric pressure to the associated bellows pocket by way of the corresponding ducts 87 and 88, and places this pocket in communication with the space within the pneumatic chest above the diaphragm 79, the reduction in pressure effecting a movement of the walls of the bellows pockets to actuate the sheet shifting mechanism to effect a movement of the sheet toward the right until the right hand opening 9 has been again covered, or until the left hand opening 9 has been uncovered.

From the foregoing it will be evident that with a sheet of standard width and free from defects, both sets of openings 8 and 9 will be covered during the time of the passage of the sheet over the tracker bar so that the sheet will be coordinated with said bar and that it will likewise be coordinated under conditions where both openings 8 are uncovered, as in the case of a sheet slightly narrower than the standard, or when both openings 8 and both openings 9 are simultaneously uncovered as in the case of a still narrower sheet.

The bleeds 43 and 58 serve the purpose of bleeding the air which has been trapped above the diaphragms 40 and 41 thus permitting the diaphragms to collapse after the sheet has been shifted to coordinate it with the tracker bar, and the openings 8 have been re-covered. The bleeds 76 and 77 serve a like purpose in conjunction with the respective diaphragms 72 and 73 and the air chambers 70 and 71 with which said diaphragms are associated.

From the foregoing it will be evident that the uncovering of the openings 8 and 9 effects the establishment of different pressure conditions in the two chambers of the pneumatic so as to maintain the music sheet in coordinated relation to the tracker bar, and by pressure conditions I mean the admission of air under atmospheric pressure into the chambers of the pneumatic, the placing of the chambers in communication with the pneumatic chest to effect an evacuation of said chambers, and also the establishment of like pressures in said chambers.

Having thus described the invention, what is claimed as new is:

1. In automatic music sheet controlling means for player pianos and like instruments, in combination, a tracker bar having the usual series of openings, a set of openings located one at each end of the said series, means for effecting lateral shifting movement of a music sheet passing over the tracker bar embodying a prime mover comprising a two-chambered pneumatic, a pneumatic chest having a negative-pressure chamber and air passages in communication with the atmosphere and also establishing communication between the chamber and re-

spective ones of the chambers of the pneumatic, valves controlling said passages and arranged in a lowered position to close communication between the respective chambers of the pneumatic and the atmosphere and open communication between said respective chambers of the pneumatic and the chamber of the pneumatic chest and in an elevated position to open communication between the respective chambers of the pneumatic and the atmosphere and close communication between said respective chambers and the chamber of the pneumatic chest, the said pneumatic chest having air chambers, diaphragms extending over said chambers and located each beneath a respective one of the said valves, and means actuated through admission of air through respective ones of the openings of the first-mentioned set for admitting air under atmospheric pressure into respective ones of the last-mentioned air chambers beneath the respective diaphragms to elevate the respective valves.

2. In automatic music sheet controlling means for player pianos and like instruments, in combination, a tracker bar having the usual series of openings, a set of openings located one at each end of said series, and a second set of openings located each in inwardly offset relation to a respective one of the openings of the first-mentioned set, means for effecting lateral shifting movement of a music sheet passing over the tracker bar embodying a prime mover comprising a two-chambered pneumatic, a pneumatic chest having a negative-pressure chamber and air passages in communication with the atmosphere and also establishing communication between the chamber and respective ones of the chambers of the pneumatic, valves controlling said passages and arranged in a lowered position to close communication between the respective chambers of the pneumatic and the atmosphere and open communication between said respective chambers of the pneumatic and the chamber of the pneumatic chest and in an elevated position to open communication between the respective chambers of the pneumatic and the atmosphere and close communication between said respective chambers and the chamber of the pneumatic chest, the said pneumatic chest having air chambers, diaphragms extending over said chambers and located each beneath a respective one of the said valves, means actuated through admission of air through respective ones of the openings of the first-mentioned set for admitting air under atmospheric pressure into respective ones of the last-mentioned air chambers beneath the respective diaphragms to elevate the respective valves, and means actuated through admission of air under atmospheric pressure through respective ones of the openings of the second-mentioned set

to interrupt such passage of air through the respective last-mentioned chamber beneath the respective diaphragm.

3. In automatic music sheet controlling means for player pianos and like instruments, in combination, a tracker bar having the usual series of openings, a set of openings located one at each end of said series, and a second set of openings located each in inwardly offset relation to a respective one of the openings of the first-mentioned set, means for effecting lateral shifting movement of a music sheet passing over the tracker bar embodying a prime mover comprising a two-chambered pneumatic, a pneumatic chest having a negative-pressure chamber and air passages in communication with the atmosphere and also establishing communication between the chamber and respective ones of the chambers of the pneumatic, valves controlling said passages and arranged in a lowered position to close communication between the respective chambers of the pneumatic and the atmosphere and open communication between said respective chambers of the pneumatic and the chamber of the pneumatic chest and in an elevated position to open communication between the respective chambers of the pneumatic and the atmosphere and close communication between said respective chambers and the chamber of the pneumatic chest, the said pneumatic chest having air chambers, diaphragms extending over said chambers and located each beneath a respective one of the said valves, means actuated through admission of air through respective ones of the openings of the first-mentioned set for admitting air under atmospheric pressure into respective ones of the last-mentioned air chambers beneath the respective diaphragms to elevate the respective valves, and means actuated through admission of air under atmospheric pressure through respective ones of the openings of the second-mentioned set to interrupt such passage of air through the respective last-mentioned chamber beneath the respective diaphragm, the said means comprising air passages establishing communication between the atmosphere and respective ones of the diaphragm covered chambers, a diaphragm located at an intermediate point in each passage, a valve associated with each of the last-mentioned diaphragms for the purpose stated, and diaphragms coating with respective ones of the last-mentioned diaphragms to seat the valve elements upon distention of the respective last-mentioned diaphragms, the openings of the second set being in communication with the spaces behind the said last-mentioned diaphragms.
4. In automatic music sheet controlling means for player pianos and like instruments, in combination, a tracker bar having the usual series of openings, a set of openings located one at each end of said series, and a second set of openings located each in inwardly offset relation to a respective one of the openings of the first-mentioned set, means for effecting lateral shifting movement of a music sheet passing over the tracker bar embodying a prime mover comprising a two-chambered pneumatic, a pneumatic chest having a negative-pressure chamber and air passages in communication with the atmosphere and also establishing communication between the chamber and respective ones of the chambers of the pneumatic, valves controlling said passages and arranged in a lowered position to close communication between the respective chambers of the pneumatic and the atmosphere and open communication between said respective chambers of the pneumatic and the chamber of the pneumatic chest, the said pneumatic chest having air chambers, diaphragms extending over said chambers and located each beneath a respective one of the said valves, means actuated through admission of air through respective ones of the openings of the first-mentioned set for admitting air under atmospheric pressure into respective ones of the last-mentioned air chambers beneath the respective diaphragms to elevate the respective valves, and means actuated through admission of air under atmospheric pressure through respective ones of the openings of the second-mentioned set to interrupt such passage of air through the respective last-mentioned chamber beneath the respective diaphragm, the said means comprising air passages establishing communication between the atmosphere and respective ones of the diaphragm covered chambers, a diaphragm located at an intermediate point in each passage, a valve associated with each of the last-mentioned diaphragms for the purpose stated, and diaphragms coating with respective ones of the last-mentioned diaphragms to seat the valve elements upon distention of the respective last-mentioned diaphragms, the openings of the second set being in communication with the spaces behind the said last-mentioned diaphragms.

atmosphere and also establishing communication between the chamber and respective ones of the chambers of the pneumatic, valves controlling said passages and arranged in a lowered position to close communication between the respective chambers of the pneumatic and the atmosphere and open communication between said respective chambers of the pneumatic and the chamber of the pneumatic chest and in an elevated position to open communication between the respective chambers of the pneumatic and the atmosphere and close communication between said respective chambers and the chamber of the pneumatic chest, the said pneumatic chest having air chambers, diaphragms extending over said chambers and located each beneath a respective one of the said valves, means actuated through admission of air through respective ones of the openings of the first-mentioned set for admitting air under atmospheric pressure into respective ones of the last-mentioned air chambers beneath the respective diaphragms to elevate the respective valves, and means actuated through admission of air under atmospheric pressure through respective ones of the openings of the second-mentioned set to interrupt such passage of air through the respective last-mentioned chamber beneath the respective diaphragm, the said means comprising air passages establishing communication between the atmosphere and respective ones of the diaphragm covered chambers, a diaphragm located at an intermediate point in each passage, a valve associated with each of the last-mentioned diaphragms for the purpose stated, and diaphragms coating with respective ones of the last-mentioned diaphragms to seat the valve elements upon distention of the respective last-mentioned diaphragms, the openings of the second set being in communication with the spaces behind the said last-mentioned diaphragms.

5. In automatic music sheet controlling means for player pianos and like instruments, in combination, a tracker bar having the usual series of openings, a set of openings located one at each end of said series, and a second set of openings located each in inwardly offset relation to a respective one of the openings of the first-mentioned set, means for effecting lateral shifting movement of a music sheet passing over the tracker bar embodying a prime mover comprising a two-chambered pneumatic, a pneumatic chest having a negative-pressure chamber and air passages in communication with the atmosphere and also establishing communication between the chamber and respective ones of the chambers of the pneumatic, valves controlling said passages and arranged in a lowered position to close communication between the respective chambers of the pneumatic and the atmosphere and open communication between said respective chambers of the pneumatic and the chamber of the pneumatic chest, the said pneumatic chest having air chambers, diaphragms extending over said chambers and located each beneath a respective one of the said valves, means actuated through admission of air through respective ones of the openings of the first-mentioned set for admitting air under atmospheric pressure into respective ones of the last-mentioned air chambers beneath the respective diaphragms to elevate the respective valves, and means actuated through admission of air under atmospheric pressure through respective ones of the openings of the second-mentioned set to interrupt such passage of air through the respective last-mentioned chamber beneath the respective diaphragm, the said means comprising air passages establishing communication between the atmosphere and respective ones of the diaphragm covered chambers, a diaphragm located at an intermediate point in each passage, a valve associated with each of the last-mentioned diaphragms for the purpose stated, and diaphragms coating with respective ones of the last-mentioned diaphragms to seat the valve elements upon distention of the respective last-mentioned diaphragms, the openings of the second set being in communication with the spaces behind the said last-mentioned diaphragms.

of the pneumatic and the atmosphere and open communication between said respective chambers of the pneumatic and the chamber of the pneumatic chest and in an elevated position to open communication between the respective chambers of the pneumatic and the atmosphere and close communication between said respective chambers and the chamber of the pneumatic chest, the said 5 pneumatic chest having air chambers, diaphragms extending over said chambers and located each beneath a respective one of the said valves, means actuated through admission of air through respective ones of the 10 openings of the first-mentioned set for admitting air under atmospheric pressure into respective ones of the last-mentioned air chambers beneath the respective diaphragms to elevate the respective valves, and means 15 actuated through admission of air under atmospheric pressure through respective ones of the openings of the second-mentioned set to interrupt such passage of air through the respective last-mentioned chamber beneath 20 the respective diaphragm, the said means comprising air passages establishing communication between the atmosphere and respective ones of the diaphragm covered chambers, a diaphragm located at an intermediate point in each passage, a valve associated with each of the last-mentioned diaphragms for the purpose stated, and diaphragms coacting with respective ones of the last-mentioned diaphragms to seat the valve 25 elements upon distention of the respective last-mentioned diaphragms, the openings of the second set being in communication with the spaces behind the last-mentioned diaphragms, and said last mentioned diaphragms being of greater area than the respective second-mentioned diaphragms. 30

6. In automatic music sheet controlling means for player pianos, in combination, a tracker car having the usual series of openings and additional pairs of relatively laterally offset openings at the ends of said series, means for effecting lateral shifting movement of a music sheet passing over the bar embodying a two-chambered pneumatic, a pneumatic chest, a wind chest conduit in communication with the interior thereof, the pneumatic chest having air passages in communication with respective chambers of the pneumatic and having intakes opening to the atmosphere, valves normally closing the intakes, a diaphragm associated with each of said valves, air passages within the pneumatic chest for admitting atmospheric air behind respective ones of the diaphragms to 35 actuate the respective valves, valve means normally closing said passages and adapted to be rendered inactive to admit air through the respective passages upon uncovering of a respective one of the said pairs of openings at either end of the bar, valves normally 40

closing the said last-mentioned passages inwardly of their intake ends and adapted to open automatically upon admission of air through the respective passages in the uncovering of the first-mentioned openings of the 70 said pairs, and pneumatic means for closing and resisting opening of the last-mentioned valves upon uncovering of the respective other ones of said pairs of openings.

7. In automatic music sheet controlling 75 means for player pianos, in combination, a tracker bar having the usual series of openings and additional pairs of relatively laterally offset openings at the ends of said series, means for effecting lateral shifting movement of a music sheet passing over the bar embodying a two-chambered pneumatic, a pneumatic chest, a wind chest conduit in communication with the interior thereof, the pneumatic chest having air passages in communication with respective chambers of the pneumatic and having intakes opening to the atmosphere, valves normally closing the intakes, a diaphragm associated with each of said valves, air passages within the pneumatic 85 chest for admitting atmospheric air behind respective ones of the diaphragms to actuate respective valves, valve means normally closing said passages and adapted to be rendered inactive to admit air through the respective 90 passages upon uncovering of a respective one of the said pairs of openings at either end of the bar, valves normally closing the said last-mentioned passages inwardly of their intake ends and adapted to open automatically 95 upon admission of air through the respective passages in the uncovering of the first-mentioned openings of the said pairs, and pneumatic means for closing and resisting opening of the last-mentioned valves upon uncovering of the respective other ones of said pairs of openings, the last-mentioned means comprising diaphragms associated with the respective last-mentioned valves, and air passages leading from the said other ones of said pairs of openings and arranged to deliver air behind the diaphragms. 100

8. In automatic music sheet controlling means for player pianos, in combination, a tracker bar having the usual series of openings and additional pairs of relatively laterally offset openings at the ends of said series, means for effecting lateral shifting movement of a music sheet passing over the bar embodying a two-chambered pneumatic, a pneumatic chest, a wind chest conduit in communication with the interior thereof, the pneumatic chest having air passages in communication with respective chambers of the pneumatic and having intakes opening to the atmosphere, valves normally closing the intakes, the said pneumatic chest having sets of spaced chambers therein, diaphragms extending over the chambers, the chambers of each set being in communication with each 115

other, the said valves normally resting upon respective ones of the diaphragms of each set and being adapted to be moved to position to uncover the intakes of the air passages and close communication between said passages and the interior of the pneumatic chest upon the admission of air behind their respective diaphragms, the pneumatic chest having air passages including intakes opening to the atmosphere and outlets communicating with the other chambers of the said sets, valves normally closing the intakes of the last-mentioned passages, pneumatic means operable upon uncovering of a respective one of the said pairs of openings at either end of the bar to actuate the respective last-mentioned valve to uncover the intake of the respective passage and thereby admit air behind the diaphragm of the respective last-mentioned chamber, valves associated with the second-mentioned diaphragm, and means operable upon uncovering of the respective other ones of said pairs of openings to resist movement of the said respective second-mentioned diaphragms.

9. In automatic music sheet controlling means for player pianos, in combination, a tracker bar having the usual series of openings and additional pairs of relatively laterally offset openings at the ends of said series, means for effecting lateral shifting movement of a music sheet passing over the bar embodying a two-chambered pneumatic, a pneumatic chest, a wind chest conduit in communication with the interior thereof, the pneumatic chest having air passages in communication with respective chambers of

the pneumatic and having intakes opening to the atmosphere, valves normally closing the intakes, the said pneumatic chest having sets of spaced chambers therein, diaphragms extending over the chambers, the chambers of each set being in communication with each other, the said valves normally resting upon respective ones of the diaphragms of each set and being adapted to be moved to position to uncover the intakes of the air passages and close communication between said passages and the interior of the pneumatic chest upon the admission of air behind their respective diaphragms, the pneumatic chest having air passages including intakes opening to the atmosphere and outlets communicating with the other chambers of the said sets, valves normally closing the intakes of the last-mentioned passages, pneumatic means operable upon uncovering of a respective one of the said pairs of openings at either end of the bar to actuate the respective last-mentioned valve to uncover the intake of the respective passage and thereby admit air behind the diaphragm of the respective last-mentioned chamber, the pneumatic chest having other chambers positioned above respective ones of the second-mentioned chambers, means establishing communication between the last-mentioned chambers and respective other ones of said pairs of openings, and diaphragms arranged over the last-mentioned chambers and co-acting with the valves upon the second-mentioned diaphragms.

In testimony whereof I affix my signature
JOHN H. KARSTETTER. [L.S.]
